UNITED STATES PATENT OFFICE.

CHARLES GORNEMAN, OF CEDAR VALLEY, UTAH.

RAILWAY-VELOCIPEDÉ.

SPECIFICATION forming part of Letters Patent No. 693,128, dated February 11, 1902.

Application filed March 11, 1901. Serial No. 50,738. (No model.)

To all whom it may concern:

Be it known that I, CHARLES GORNEMAN, a citizen of the United States, residing at Cedar Valley, in the county of Utah and State of Utah, have invented certain new and useful Improvements in Railway-Velocipedes; and I do hereby declare the following to be a full, clear, and exact description of the invention, such as will enable others skilled in the art to 10 which it appertains to make and use the same.

My invention relates to bicycles; and its object is to provide an attachment which can be readily attached to and removed from the ordinary safety-bicycle to adapt it to be ridden upon a railroad-track.

Other objects of my invention are, first, to construct a frame which can be collapsed when attached to the bicycle, so as to occupy as little space as possible when riding upon 20 the highway; second, to provide means for keeping the supporting-wheel in contact with the rail, and, third, to arrange the flange-wheels so as to avoid derailment of the vehicle when crossing a switch or cross-rail.

Further objects and advantages of this invention will appear in the following description, and the novel features thereof will be particularly pointed out in the appended claims.

In the accompanying drawings, forming a part of this specification, Figure 1 is a perspective view of a bicycle mounted upon railroad-tracks and provided with the attachment and embodying all the objects of my invention.

Fig. 2 is an end view of the bicycle and its attachment mounted on the railroad-tracks. Fig. 3 is a detail perspective of the supporting-wheel, showing the manner of mounting its flange-roller. Figs. 4, 5, and 6 are detail

views of the clamps for clamping the attachment to the frame of the bicycle. Fig. 7 is a detail perspective of the hanger for the flange-roller. Fig. 8 is a perspective of the bicycle, showing a modified form of flange-rollers, the 40 supporting-rods being broken away. Fig. 9 is a longitudinal section of the flange-rollers shown in Fig. 8.

Referring to the drawings, in Figs. 1 and 2 an ordinary pneumatic-tire safety-bicycle is 50 shown mounted on the rail and supported

thereon by means of a frame comprised of three telescoping transverse rods 1, 2, and 3, which converge and carry the axle of the supporting-wheel 4, mounted on the opposite rail. Mounted upon a depending hanger 5, which 55 is attached to and disposed at right angles to the axle of the supporting-wheel, is a rubber-tired flange-wheel 6, which extends a slight distance below the supporting-wheel 4 and inclines slightly from the horizontal, so as to 60 give it a tendency to roll downward when in contact with the edge of the rail, thereby keeping the supporting-wheel in contact with the rail. As shown, the transverse rod 1 is clamped to the handle-bar at a by a clamp 65 shown in Fig. 4 and prevents the head of the bicycle from turning, while the same clamp is used to attach rods 2 and 3 to the front and rear forks of the bicycle, as shown at a' and b. These clamps are especially constructed 70 for the attachment, so that they can be readily detached from the frame of the bicycle when it is desired to travel upon the highway. They consist of a hooked member A, externally screw-threaded at its shank end 75 and screwing within the member B, which is attached to the end of the transverse rods 1, 2, and 3. As it is screwed down the clamping-bolt C, which extends centrally through the shank of the hook, engages the bicycle-frame or other support, as will be easily understood from Fig. 4 of the drawings.

Depending from the frame of the bicycle are hangers 7 and 8, carrying the guide-wheels 9 and 10, which run beside the rail and extend 85 a slight distance beneath the wheels of the bicycle to prevent the derailment of the same. However, they do not contact with the rail only upon curves and when there is a slight deviation in the gage of the track, as when 90 crossing switches, &c. The hanger 8 is hung from the axle of the rear wheel and is further braced by a bar 11, which extends from the axle of the guide-wheel 10 to the rear forks of the bicycle and is clamped thereto by means 95 of the clamp c. (Shown in Fig. 6.) At a point d intermediate of its ends this bar is engaged by a clamp attached to the transverse bar 3 and which clamp consists of a member D, pivoted on the bar 3 and operated by a 100

clamping-collar *e*, as shown in Fig. 5. The hanger *7* is secured to the bar *2* by means of this same clamp, Fig. 5, and is indicated at *e* in Fig. 1, the end of the hanger extending upward and engaging the foot-rest on the front fork of the bicycle. The guide-wheel *9* is further supported by a brace *7^a*, having the clamp shown in Fig. 4 upon its end, as shown at *f*, Fig. 1.

10 To prevent the handle-bars from turning, the clamp shown in Fig. 5 is attached to the bar *1* and engages the upper bar of the bicycle-frame at *g*. It will be seen that these clamps are easily operated and insure facility in attaching and detaching the device from the bicycle. By pivoting the clamp to the top bar of the frame it prevents the head of the bicycle from turning, and the front wheel is always kept straight.

15 20 As stated before, the guide-wheels *9* and *10* do not engage the rail only where there is a slight deviation in the gage, and this is accomplished by providing upon the supporting-wheel *4* a flanged rubber tire *4^a*, which engages the outer edge of the rail; but when crossing frogs or other breakage in the track the supporting-wheel will slide laterally and allow the guide-wheels *9* and *10* to engage the rail, while the flange-wheel *6* will be disengaged from the rail and free to pass the frog or switch, thus preventing derailment of the velocipede.

25 30 The inner end of the axle of the supporting-wheel is provided with a face-plate *12*, to which all three of the transverse supporting-rods are attached, and which also carries the flange-roller *6*, hereinbefore described. I have shown a detail perspective of this plate and the hanger for the flange-roller in Fig. 7. 35 40 As stated before, the roller is inclined slightly from the horizontal, caused by bending the hanger *5* rearwardly, and thus should it contact with an obstruction on the track it would easily ride over the same rather than drag it.

45 50 In Figs. 8 and 9 I have shown a modified form of a flange-roller, which may be used when the tracks are covered with snow or ice. The objects of these additional attachments are to cut the snow and ice from the track and prevent the derailment of the bicycle and to obviate the liability of the bicycle leaving the track when there are variations of gage in the same—namely, at switches, crossings, and the like. In this modification I have shown 55 60 the flange-rollers extending forward of the front wheel and rearwardly of the hind wheel, as shown in Fig. 8. This is accomplished by throwing the hangers *8* and *7* outwardly and divergently from the frame, the brace-bar *11* necessarily being longer to permit its engagement with the supporting-rod *3*. I employ 65 an axle *14*, carrying the guide-wheels *9* and *10*, mounted thereon, and which axle extends across the rail, having mounted upon it the sleeve *16*, provided with the flaring flange *17* and which is held upon the axle by the washer

20 and nut *18*. The nut *18* may either be screw-threaded to engage the axle or may be keyed thereto by the pin *19*. *8* and *11* of Fig. 9 indicate the hangers and brace-bars, (shown 70 in Figs. 1 and 2,) which support the axle carrying the guide-wheel and flange-roller. Mounted upon the forward end of the axle is a roller *15*, which tapers inwardly and which is adapted to engage and roll upon the wing 75 of the frog while the guide-wheel *10* crosses the point of the frog, thus preventing derailment of the vehicle. The flaring flange *17* serves to cut the ice or snow from the track and at the same time insures smoothness in 80 its course, for should the meeting ends of the rail be uneven the outward flare of the flange will easily ride the projection.

85 The advantages of this construction will be apparent to any one familiar with this class of devices in that it is extremely simple in its construction, strong, durable, effective in its operation, and comparatively inexpensive to manufacture.

Having thus described my invention, what I claim is—

1. In a railroad-bicycle, the combination with a bicycle, of a frame detachably connected thereto and carrying a supporting-wheel, and a horizontally-disposed flange-roller depending below the supporting-wheel, substantially as described.

2. In a railroad-bicycle, the combination with a bicycle, of a frame connected thereto and carrying a supporting-wheel, the outer 100 ends of the bars of the frame being secured to the axle of the supporting-wheel, a depending hanger carrying a flange-roller for the supporting-wheel, said roller being disposed slightly from the horizontal to insure 105 a downward rolling tendency to the same, substantially as described.

3. The combination with a bicycle, of a frame composed of three transverse bars, two of which are detachably connected to the 110 front and rear forks of the bicycle respectively and the third detachably connected to the upper bar of the frame and extending into engagement with the handle-bar to prevent the front wheel of the bicycle from 115 turning, a supporting-wheel carried by the frame, a plate to which all three of the bars are connected, said plate having a depending hanger and a horizontal flange-wheel journaled thereon, and guide-wheels supported from the front and rear forks of the 120 bicycle, substantially as described.

4. In a railroad-bicycle, the combination with a bicycle having guide-wheels suspended from its frame, of a frame connected 125 thereto, said frame consisting of transverse bars detachably secured at one end to the bicycle-frame, a plate secured to the other ends of the bars, an axle carried by said plate, a supporting-wheel provided with a 130 flanged rubber tire journaled on said axle, a flange-wheel suspended from the plate, and

means whereby the flange-wheel is caused to keep the supporting-wheel in contact with the top of the track, substantially as specified.

5. In a railroad-bicycle, the combination with a bicycle, of a frame comprising converging, telescoping, transverse bars detachably secured thereto, said frame carrying a supporting-wheel and a depending flange-roller, the latter being disposed slightly from the

horizontal to insure a downward rolling tendency to hold the supporting-wheel in contact with the rail, substantially as described.

In testimony whereof I affix my signature in presence of two witnesses.

CHARLES GORNEMAN.
